GARMENT BAGGER.

Frederick William Strobel, Washington, D. C.

Application April 26, 1939, Serial No. 270,255

3 Claims. (Cl. 248—161)

This invention relates to garment baggers by the use of which a garment is supported on a hanger while the bag is being pulled down over the garment.

5 The present invention has for an object to provide a portable device for the purpose stated which can be easily manufactured at low cost and which, while comparatively light will be so constructed as to be sturdy, and will require few 10 if any repairs or replacements of parts after long continued use.

Another object is to provide a device of the character stated in which the garment holding rod may be easily released to drop down out of 15 the way when desired, in such manner that it will not rebound to any considerable extent when released.

Further it is an object to provide a garment 20 bagger, in which the garment holding rod may be securely held at any raised position desired, regardless of the wear on the rod and the clutch device.

Further it is an object to provide, in a bagger, a novel rod clutch and guide unit and a novel 25 bumper or buffer unit which cooperate in fulfilling the aforesaid objectives.

Other objects will in part be obvious and in part be pointed out hereinafter.

To the attainment of the aforesaid objects and 30 ends the invention still further resides in the novel details of construction, combination and arrangement of parts, all of which will be first fully described in the following detailed description, and then be particularly pointed out in the 35 appended claims, reference being had to the accompanying drawing in which—

Fig. 1 is a cross-section of the device in elevation.

Fig. 2 is a perspective view of the clutch unit.

40 Fig. 3 is a cross-section on the line 3—3 of Fig. 1.

In the drawing, in which like numerals of reference indicate like parts in all of the figures, 1 indicates a heavy base having a threaded aperture 2 to receive the threaded end 3 of a tubular post 4 having a cover plate 5.

6 represents a garment holding rod forked or otherwise formed as at 9 to receive an ordinary clothes hanger. The rod 6 is provided at its 50 other end with a button 7 held in place on the end of a rod 6 by a set screw 8 or in any other suitable way.

10 indicates the casing of the clutch unit which casing has a chamber 11 in which is located an eccentric roller 12 mounted on the axis 13.

The clutch unit is mounted within the post 4 by the screws 15 and the threaded holes 14. A screw hole 16 is provided in the top surface of the casing 10 to receive the screw 17 to retain the cover plate 5.

18 indicates a passage in the casing 10 for the rod 6.

A buffer block 19 having an impact washer 20 of leather or similar material is held to the bottom of the base by threaded cap screws 21.

10 Recesses 22 are provided within the block 19 to receive the buffer springs 23.

A hole 24 is located within the casing 10 for the release rod 25 and within the base is located a foot lever 26 having a recess 27 in one end to 15 receive the end of the release rod 25. The other end of the foot lever 26 projects through the base 1.

29 indicates the pivot of the lever 26.

In operation the rod 6 is pulled out by the operator to the position desired where it will remain no matter how much weight is placed on the rod. The harder the rod 6 is forced downward the tighter is the gripping action of the eccentric roller.

25 After the rod is pulled out to the desired height and a garment placed thereon a garment bag is pulled down over the garment and the rod after which the operator grasps the garment hanger and steps on the foot lever 26 which releases the rod 6 allowing it to fall until it hits the buffer.

30 The impact washer 20 serves to deaden the impact sound and cooperates with the buffer springs in absorbing the shock. The springs are 35 preferably so designed that they will give as little rebound force to the rod as possible. The button on the lower end of the garment holding rod increases the area of contact with the buffer and thereby distributes the impacting force over a larger area than that of the cross section of the rod proper and hence reduces the wear of the washer.

40 From the foregoing description, taken in connection with the accompanying drawing, it is 45 thought that the construction, operation and advantages of the invention will readily appear to those skilled in the art.

What I claim is:

1. In a garment bagger, a base, a hollow post 50 vertically mounted on said base, a clutch unit fixedly mounted within said hollow post at its upper end, a garment holding rod vertically slideable through said clutch unit, said clutch unit comprising a block having a chamber, an eccentric

- tric roller pivotally mounted in said chamber, said block having a rod passage intersecting said chamber through which intersection said roller contacts said garment holding rod to arrest its downward movement, another rod within said post and base to move said roller out of contact with said garment holding rod, and a foot operated lever projected out of said base and also engaging said another rod to operate the same.
10. 2. In a garment bagger in which is provided a hollow post, a chambered base on which the post is mounted and a garment holding rod vertically movable in said post and arranged to fall lengthwise by gravity when released; a block in the base 15 extending across the lower end of the post in line with said rod, a button on the lower end of the rod, said block having a leather pad on which the button rests, and springs carried by

studs secured to said base and slidably securing said block in place as a shock absorbing device for the rod.

3. A garment bagger comprising a tubular post, a garment supporting rod mounted for vertical sliding movement in said post, a frictional locking member mounted in the post and engaged with said rod for releasably securing the rod in raised position, said frictional locking member comprising a block held in the post and including 10 a garment-supporting-rod-engaging roller cam and having a guide aperture, a slidably mounted rod-releasing member projecting through said guide aperture to engage said roller cam for actuating the same to release position, and a pivotally 15 mounted foot lever operatively connected to said rod-releasing member for elevating the same.

FREDERICK WM. STROBEL.
